US00D873768S

(12) **United States Design Patent** (10) **Patent No.:** **US D873,768 S**
(45) **Date of Patent:** **** Jan. 28, 2020**

(54) **CHARGER FOR ELECTRIC VEHICLES**

(71) Applicants: **Jung Minkyo**, Daegu (KR);
DAEYOUNG CHAEVI CO., LTD.,
Daegu (KR)

(72) Inventor: **Jung Minkyo**, Daegu (KR)

(73) Assignee: **DAEYOUNG CHAEVI CO., LTD.**,
Daegu (KR)

(**) Term: **15 Years**

(21) Appl. No.: **35/505,118**

(22) Filed: **Dec. 13, 2017**

(80) **Hague Agreement Data**

Int. Filing Date: **Dec. 13, 2017**

Int. Reg. No.: **DM/101461**

Int. Reg. Date: **Dec. 13, 2017**

Int. Reg. Pub. Date: **Jun. 15, 2018**

(30) **Foreign Application Priority Data**

Jun. 13, 2017 (KR) 3020170026876
